ADJUSTING MECHANISM FOR THE BREAKING ROLLERS OF FLAX-BREAKING MACHINES.

Specification of Letters Patent.

Patented Feb. 7, 1922.

Application filed November 18, 1919. Serial No. 338,933.

(GRANTED UNDER THE PROVISIONS OF THE ACT OF MARCH 3, 1921, 41 STAT. L., 1313.)

To all whom it may concern:

Be it known that I, IGNAC ETRICH, a subject of the Czecho-Slovak Republic, residing at Oberaltstadt, near Trautenau, Bohemia, have invented certain new and useful Improvements in Adjusting Mechanism for the Breaking Rollers of Flax-Breaking Machines (for which I have filed applications in Austria, August 21, 1916, Patent No. 76,512 issued; Hungary, December 30th, 1916, Patent No. 71831 issued; Germany, August 24th, 1916, Patent No. 299,547 issued; Holland, August 17th, 1917, Patent No. 3861 issued; Belgium, August 27th, 1917, Patent 272,447, issued; France, August 27th, 1919; Sweden, Sept. 8th, 1919); and I do hereby declare the following to be a full, clear, and exact description of the invention, such as will enable others skilled in the art to which it appertains to make and use the same.

This invention relates to flax breaking machines in which the retted stalks of flax or hemp are caused to pass through a series of fluted rollers for crushing their lignous parts. Such breaking machines are in many cases advantageously used as a substitute for the ordinary flax brake, but they require an exact and rapid governing of the pressure of the rollers and therefore an exact adjustment of the fluted rollers for securing for a given sort of flax the best conditions of working.

Heretofore this adjustment of the fluted rollers was effected by separately adjusting the upper roller of each pair but as a flax breaking machine is usually provided with a large number of pairs of rollers (20 to 30 and even more) an exact and rapid adjustment of each individual pair of rollers can not be practically obtained.

It has also been proposed to adjust simultaneously all the fluted rollers from a common shaft by means of suitable bevel gears and screw spindles for each pair of rollers but even this does not permit to obtain the required exactness and direct action, mainly on account of the lost motion in the adjusting devices (consisting of a plurality of parts movable relatively to each other) of various pairs of adjusting rollers and besides this known adjusting device permits at the best to adjust all the rollers by equal

amounts, but does not permit to adjust the rollers in such a manner that the normal distance between the rollers of any pair is in a predetermined ratio differing from one with the normal distance between the rollers of another pair, no matter how the individual pairs of rollers may be adjusted.

This inconvenience is overcome according to the present invention by moving simultaneously the bearings of all the upper rollers of a breaking machine relatively to the fixed bearings of the lower rollers by means of a pressing frame common to all the upper rollers.

In the annexed drawing Fig. 1 is a part of a plan view, Fig. 2 a part of a side elevation on a larger scale of an embodiment of the present adjusting apparatus, and Fig. 3 is an end elevation partly in section of one corner of the apparatus.

1 are the bearings of the upper rollers of a breaking machine; these bearings are suitably guided in the machine. A frame 3 consisting of two longitudinal bars connected with each other, if desired by transverse bars, rests upon the bearings 1 of the upper rollers and powerful springs 2 are interposed between the bearings and the frame. The latter contains the female threads for bolts 4 which as shown in the drawing are free to revolve in the machine frame, but are prevented from moving axially and worm wheels 5 revolving with the bolts 4, but prevented from moving axially engage with large worms 6 on shafts 7 running along two opposite sides of the adjusting frame 3 driven simultaneously and at the same speed by bevel gearing 8 from a hand wheel 9 at the delivery end of the breaking machine. There may be any desired number of bolts 4 evenly distributed at each of the longitudinal sides of the adjusting frame 3; in most cases it will be sufficient to provide one such bolt 4 at each of the four corners of the adjusting frame. The attendant at the hand wheel 9 will readily see from the state of the broken material delivered by the machine what readjustment if any of the breaking rollers is required for the raw material under treatment and then may raise or lower the adjusting frame as an entirety by simply turning the hand

wheel 9 in the one or in the other direction whereby also the pressure between the two rollers of all the pairs is simultaneously increased or reduced.

5 Usually the adjusting frame 3 will be held parallel to the plane of the fixed axes of the lower breaking rollers not shown. If desired or found necessary to give the adjusting frame a slight inclination relatively 10 to this plane, for instance to make the distance between the rollers of the pairs at the entering end of the machine slightly greater than at the delivery end, it is sufficient to impart to the bolts 4 at the 15 entering end another adjustment than at the delivery end. The distance between the rollers of the pair at the entering end may then be always in the same ratio to that of the rollers of the pair at the delivery end 20 by making the speed relation between the shafts 7 and the bolts 4 at the entering end different from that at the delivery end, for instance by taking, all other things being equal, worm wheels 5 of a larger number of 25 teeth for the delivery end than for the entering end.

The bolts 4 might engage with the machine frame by means of a screw thread having another pitch than the female thread in 30 the adjusting frame. They would then act in the manner of differential screws or the bolts 4 might be prevented from revolving and from moving axially in the machine frame, while the worm wheels are free to 35 revolve in the adjusting frame but prevented from moving axially, the female thread being in the worm wheel and the female thread for the bolt in the machine frame being dispensed with. Instead of 40 bolts 4 and female threads any other mechanism might be operated by the hand wheel 9 and, acting on the adjusting frame as an 45 entirety, might be used for adjusting purposes for instance cranks or eccentrics journaled in the adjusting frame, and operated from the shaft 7, 7 by means of worm gearing, the rods of the cranks or eccentrics being connected with the machine frame, or toggle levers interposed between the 50 adjusting and the machine frame might be used, the middle joints of these toggle levers being actuated by the shafts 7.

Claims.

1. In a flax breaking machine the combination of a plurality of pairs of breaking 55 rollers, fixed bearings for the lower rollers of the pairs holding the axes of such lower rollers substantially in one plane, movable bearings for the upper rollers of the pairs, means for guiding such bearings of upper 60 rollers in lines substantially at right angles to the said plane, an adjusting frame extending over all the upper rollers, springs interposed between such adjusting frame and the bearings of the upper rollers and means 65 for moving the adjusting frame as an entirety relatively to the said plane, the amount by which the adjusting frame is moved at right angles to the said plane above one end of the series being in a predetermined constant ratio to the amount by which the adjusting frame is moved at right angles to the said plane above the other end of the 70 series.

2. In a flax breaking machine the combination of a plurality of pairs of breaking rollers, fixed bearings for the lower rollers of the pairs holding the axes of such lower rollers substantially in one plane, movable 75 bearings for the upper rollers of the pairs, means for guiding such bearings of upper rollers in lines substantially at right angles to the said plane, an adjusting frame extending over all the upper rollers, springs interposed between such adjusting frame and the bearings of the upper rollers and means 80 for moving the adjusting frame as an entirety relatively to the said plane, such means including a hand wheel located at the delivery end of the machine, the amount by 85 which the adjusting frame is moved at right angles to the said plane above one end of the series being in a predetermined constant ratio to the amount by which the adjusting frame is moved at right angles to 90 the said plane above the other end of the series.

In testimony whereof, I affix my signature, in presence of two witnesses.

IGNAZ ETRICH.
